H. F. Shaw

UNITED STATES PATENT OFFICE

HENRY F. SHAW, OF WEST ROXBURY, ASSIGNOR TO JAMES A. WOODBURY
AND SOLOMON S. GRAY, OF BOSTON, MASSACHUSETTS.

IMPROVEMENT IN PULLEY-BLOCKS.

Specification forming part of Letters Patent No. 79,264, dated June 23, 1868.

To all whom it may concern:

Be it known that I, HENRY F. SHAW, of West Roxbury, in the county of Norfolk and State of Massachusetts, have invented a new and useful Improvement in Pulley-Blocks, of which the following is a full, clear, and exact description, reference being had to the accompanying drawings, making a part of this specification, in which—

Figure 1 represents a perspective view of a pulley-block embodying my invention. Fig. 2 is a transverse vertical section of the same, and Fig. 3 is a section on the line *x y* of Fig. 2. Fig. 4 is an end view of the eccentric-sleeve.

The object of my invention is to produce a pulley-block which will be very simple in its construction, effective in operation, and capable of sustaining a weight at any desired height without the aid of a ratchet and pawl or any other holding device, and also to dispense with the use of a lower or secondary sheath.

The nature of my invention consists in the application to the construction of a pulley-block of a differential gear, as described in a patent granted to me March 10, 1868, and numbered 75,304, in which two wheels, having, respectively, an external and internal gear, are hung eccentrically upon a shaft, which is free to revolve independently of either gear.

In my present invention the gears are arranged upon an eccentric-sleeve, which is keyed to the shaft that passes into or is journaled in the two sides or frame of a pulley-block. Upon the same shaft that bears the eccentric-sleeve is secured the winding-wheel, by which the shaft and eccentric are rotated.

To the pulleys connected with the gears are attached cords or ropes, which sustain the weight to be lifted, one end being attached to the pulley connected to the internal, and the other to that connected to the external gear, so that, as the eccentric-sleeve is rotated, the pulleys will act mutually as buttresses, and thus overcome any resistance offered to the tendency to relative motion.

Both pulleys being free upon the actuating sleeve or shaft, and the two ropes drawing opposite directions, a perfect equilibrium tension is maintained.

Referring to the drawings, A represents the frame of a pulley-block, provided with a swiveled hook B. C represents a shaft or bearing passing through or hung in the sides of the frame. On the shaft C is placed a sleeve, consisting of a cylindrical portion, 1, upon which is secured the winding-wheel D, carrying the rope h. 2 and 3 are eccentrics formed on opposite sides of the sleeve. The ends of the ropes, e and f, are attached, respectively, to the pulleys E and F, and the other ends to the swiveled hook G, that sustains the weight H. The pulley E carries the internal and the pulley F the external gear.

Upon putting the driving-wheel in motion by pulling the rope h, the eccentric-sleeve will be rotated, and as the two gears move independently of the eccentric-sleeve, and are resisted in their motion by an equal force, they will revolve slowly in opposite directions, thus winding up the cords that sustain the weight to be raised.

The collar is made separate from the actuating-shaft, so as to admit of its being easily inserted between the sides of the pulley-block frame.

Having thus described my invention, which I claim as new, and desire to secure by Letters Patent, is—

The combination, in a pulley-block, of the winding-wheel D, the differential gear, pulleys E F, and an eccentric-sleeve, substantially as and for the purpose set forth.

In testimony whereof I have signed my name to this specification in the presence of two subscribing witnesses.

HENRY F. SHAW.
